LEVER TYPE REVERSIBLE RIGHT OR LEFT JALOUSIE OPERATOR

Robert S. Cline, Bradenton, Fla., assignor to V. E. Anderson Manufacturing Company, Inc., Bradenton, Fla., a corporation of Kentucky

Application June 3, 1957, Serial No. 663,169

9 Claims. (Cl. 74—491)

This invention relates generally to operators for the operating mechanism for pivoted closures, and refers more particularly to an operator for jalousie operating mechanism. One of the essential objects of the invention is to provide a construction which is mountable in operative condition on either the right hand or left hand side of a jalousie frame and which is quickly exchangeable from one side to the other. It is a further object to provide a construction which may be used as a replacement for other types of operators and without disfigurement in appearance. Still further it is an object to provide a construction which is composed largely of cast aluminum alloy elements and which has all the required strength for taking care of the stresses to which it is subjected.

With these objects in view the invention consists in the construction as hereinafter set forth.

In the accompanying drawings:

Figs. 1 and 2 are vertical sections through a jalousie window and showing the end members for the panes thereof in opened and in closed positions respectively.

Fig. 3 is a fragmentary front elevation of the jalousie window illustrated in Figs. 1 and 2.

Fig. 4 is an enlarged fragmentary sectional view through the operator in an axial plane thereof.

Fig. 5 is a cross section on line 5—5 of Fig. 4.

Fig. 6 is a fragmentary elevation of a lever handle, and illustrating the rock arm in full and dotted lines respectively, to show the different positions in which the lever handle and rock arm may be assembled when the operator is changed from one side to the other of the jalousie frame.

Fig. 7 is a fragmentary elevation of the operator, showing the bearing member for the lever handle attached to a side rail of the jalousie frame and concealing the slot or cutaway portion therein, and showing parts broken away and in section.

Fig. 8 is a vertical sectional view through a side rail of the jalousie frame not used for the operator mounting, and showing a blank for concealing the slot or cutaway portion in said side rail.

Fig. 9 is a fragmentary sectional elevation of a side rail, taken from the inner side thereof, and showing the actuating bar for the jalousie operating mechanism in locked position.

Fig. 10 is a detached enlarged front elevation of the member K and nut K⁴ constituting a part of the adjustable connecting means between the operator and the jalousie operating mechanism, and showing the cylindrical extension K⁶ of the nut K⁴ in registration with the circular opening K⁷.

Fig. 11 is a cross sectional view taken substantially on the line 11—11 in Fig. 1.

Fig. 12 is a view similar to Fig. 10, but showing the cylindrical extension K⁶ of the nut K⁴ held by the projection K¹⁰ out of registration with the circular opening K⁷.

Fig. 13 is a perspective view of the member K, pin

2

K' and actuating bar G with a portion of the latter broken away.

Jalousie windows are controlled by various types of operators, some of which are movable in a vertical slot in the frame. In my invention the mechanism is actuated by a rotatively movable lever handle located in a convenient position on the jalousie frame. If such construction is used as a replacement for another type of operator, and one in which the jalousie frame is slotted, it is desirable to conceal this slot. I have therefore devised a construction in which the operator unit is mounted on a side rail of the jalousie frame to engage and conceal a slot or cutaway portion therein and to form a rigid attachment to the side rail. As above stated, the operator is composed largely of cast aluminum alloy elements, but as it is subjected to some considerable stress in its operation, it is reinforced by stronger metal.

Generally described, the operator includes a cast aluminum alloy lever handle A pivotally mounted on a bearing member C having a portion C' fitting within a slot or cutaway portion B³ in a side rail B of the jalousie frame. The side rail B is formed of an extruded aluminum channel bar which received and conceals portions of the operating mechanism and the bearing member C for the lever handle A is mounted on an angle flange B' of said side rail adjacent to a transversely extending web portion B² thereof. To impart the requisite strength to the handle A, it has cast within a hub portion A' of said side rail a polygonal pin D that is preferably hexagonal and is formed of harder metal. Such pin D is coaxial with the hub portion A' has a polygonal portion D' extending outward beyond the same and constituting an endwise extension thereof. The pin D has a portion D² of reduced diameter within the hub portion A', and a part 8 of said hub portion encircles the reduced portion D² and forms an anchor for holding said pin D from axial displacement. Beyond the polygonal portion D' is an end portion D³ that is further reduced in diameter and is threaded. Non-rotatably sleeved upon the polygonal portion D' of the pin D is a bushing E which interiorly conforms to and fits about the polygonal exterior of the portion D' of the pin, but is externally cylindrical, as indicated at E', to rotate within a bore C⁵ in the hub C⁴ of the bearing member C. A rock arm F is rigidly secured to the outer projecting end portion 9 of said bushing E so that when the latter is engaged with the polygonal portion D' of the pin D, as just described, a torque transmitting connection is formed between the handle A and said rock arm F. The bearing member C is of a length somewhat greater than that of the slot B³ in the rail B and has at opposite ends thereof portions C² which overlap the side rail B and are attached thereto by screws C³. However, the portion C' within the slot B³ in the side rail B will receive the maximum operating stresses and not the screws C³. To mount the handle A on the bearing member C projecting polygonal portion D' of the pin D is first inserted from the outside of the side rail B into the bore C⁵. The bushing E is then sleeved upon the polygonal portion D' of said pin from the inside of the side rail B and is held against displacement by a nut D⁴ engaging the threaded end portion D³. The rock arm F is connected by a substantially aligned flat actuating bar G to the jalousie operating mechanism. The construction of the latter is not a part of the instant invention, but generally described, is of the following construction:

The separate panes H, H' of the jalousie are mounted in metallic end members I which are pivotally attached at I' to the side rail B. Actuating arms I² extend on the opposite side of the pivots and are connected to the back of a channel-shaped common connecting bar J. Thus a movement of said bar J longitudinally will simul-

aneously turn each of the members I on its pivot from the closed position where the panes H, H' overlap each other, as shown in Fig. 2, to the open position, shown in Fig. 1 or vice versa as desired. Without further description of the jalousie, its connection to the operator is through the actuating bar G, the lower end of which is pivotally connected at 10 to the rock arm F, while its upper end is pivoted at 11 to an adapter member K mounted on the connecting bar J. Thus the rocking movement of the handle A will be transmitted through the rock arm F, actuating bar G, and member K to the connecting bar J to operate the end members I and panes H and H' of the jalousie window.

As my improved operating mechanism is sometimes used as a replacement for that of a previously installed jalousie, it is desirable to provide adjustment for the connections. Thus, as shown in Fig. 11 the connecting bar J may have a bore J' therethrough for engaging a pivot of the old operator and this bore is utilized for the attachment of the member K. However, its position may not be right to fit the new installation. I have, therefore, provided a headed pin K' having a cylindrical portion 12 for engaging said bore J' wherever located, and having a threaded shank K² for passing through a longitudinally extending elongated slot K³ in the member K. A nut K⁴ is on one side of the member K beside a longitudinally extending flange K⁵ thereof which holds said nut K⁴ from turning while guiding the movement of the nut K⁴ lengthwise of the flange K⁵, and thereby guiding the pin K' lengthwise of said elongated slot K³. The nut K⁴ is provided at one side thereof with a cylindrical axial extension K⁶ which is initially inserted through a circular opening K⁷ at the upper end of the slot K³, and then engages the elongated slot K³. This extension K⁶ has an annular groove K⁸ therein that receives a guide flange K⁹ that extends along the edges of said slot K³ at opposite sides and at the bottom thereof, but terminates below said circular opening K⁷. Thus the nut K⁴ may be assembled with the member K by first inserting the cylindrical extension K⁶ in the circular opening K⁷ and then moving the extension K⁶ longitudinally of the slot K³ so that the groove K⁸ will receive the guide flange K⁹. To prevent accidental disengagement of the nut K⁴ from the member K after engagement of the annular groove K⁸ with the flange K⁹, the upper edge of the opening K⁷ is pinched or otherwise distorted to provide a projection K¹⁰ that serves as an abutment for the cylindrical extension K⁶ and effectively prevents subsequent registration or alignment of said cylindrical extension K⁶ with the circular opening K⁷. However, the cylindrical extension K⁶ of the nut K⁴ is then free to slide lengthwise of the slot K³ between the projection K¹⁰ and the lower end of said slot K³. Thus the projection K¹⁰ prevents the return of the cylindrical extension K⁶ to its position of entry in the opening K⁷. Lugs 13 and 14 respectively at the upper and lower ends of the member K engage the channel of the connecting bar J to guide the member K lengthwise of said bar J. The assembled parts just described, together with the other portions of the operator may be shipped as a unit to wherever it is to be installed and without danger of loss of any part through accidental disengagement. To attach the operator to the jalousie, the pin K' is unscrewed and detached from the nut K⁴ so that said pin K' may be inserted in the bore J' of the connecting bar J. The threaded shank K² is then reengaged with the nut K⁴ which can then be slid lengthwise of the slot K³ to the proper location, and upon tightening the pin K' the parts will be clamped in this assembled position.

When the end members I and panes H and H' of the jalousies are closed it is desirable to lock them in such closed position. This may be accomplished as illustrated in Fig. 9 in which the rock arm F is turned by the lever handle A into a position where the upper end of the rock arm F abuts and is stopped by the web portion

B² of the frame rail B. In this position, the pivotal connection 10 has passed beyond its dead center, and the end members I of the jalousie window are in closed position. Actually, the arrangement of the bushing E and the pivotal connections 10 and 11 is such that the upper end portion of the rock arm F will be held in contact with the web portion B² after the pivotal connection 10 is beyond its dead center, and accordingly the actuating bar G and jalousie operated mechanism will be locked in closed position. A change of the operator from one side to the other of the jalousie frame, such for example from the right side to the left side of the jalousie frame, would cause the lever handle A to be in the wrong angular relation or position to the rock arm F, bearing member C, and side rail B. To avoid such result, the lever handle A and the rock arm F are relatively positioned with an included angle therebetween which is one-half the angular magnitude between adjacent sides of the polygonal portion D' of the pin D. Also the lever handle A and rock arm F are positioned relative to the polygonal portion D' of the pin D so that the lever handle A may be changed from a given angle on one side of the rock arm F to an equal angle on the opposite side thereof, by first disassembling or withdrawing the polygonal portion D' of the pin D from the bushing E fixed to the rock arm F, then turning or shifting the lever handle A from one side to the opposite side of the rock arm F, so that the polygonal portion D' will be turned or shifted from one side to the next, and then assembling or inserting the turned or shifted polygonal portion D' in the bushing E to retain the lever handle A in its new angular position relative to the rock arm F. The different positions in which the lever handle A and rock arm F may be assembled are illustrated in full and in dotted lines respectively in Fig. 6. Thus, the locations of the lever handle A in open and in closed positions of the end members I and panes H and H' of the jalousie may be made the same relative to opposite sides of the frame when mounted on the right and left sides respectively thereof.

The operator as above described may be easily applied for operation of any jalousie construction. If it is used to replace operators which necessitate the slotting or cutting away of the side rails B of the jalousie frame, the bearing member C will cover such slot or cutaway portion. If the rails on both sides of the frame have been or are slotted, the bearing member C may be used to cover the slot in the side rail where the operator is mounted, and a solid blank L similar in shape to the bearing member C may be used, as illustrated in Fig. 8, for closing the slot or cut-out in the other side rail on which the operator is not mounted.

What I claim as my invention is:

1. An operator assembly for a jalousie operating mechanism; comprising a bearing member having a bore therethrough, a handle having a hub upon one side of said bearing member, a pin anchored within said hub and having a polygonal portion extending axially of said bore, said pin being provided beyond the other side of said bearing member with a projecting end portion, a bushing at one end of and separate from said hub, said bushing having a portion extending axially of said bore and nonrotatably sleeved upon the polygonal portion of said pin, the axially extending portion of said bushing being rotatable within said bore and constituting the pivot for said handle, said bushing being provided beyond said other side of said bearing member with a projecting end portion, a rock arm nonrotatably mounted on the projecting end portion of said bushing and having a portion attachable to an actuating bar for the jalousie operating mechanism for operating the same from said handle, and means engaging the projecting end portion aforesaid of said pin adjacent said rock arm and cooperating with said hub for retaining the axially extending

polygonal portion of said pin in assembled relation with the axially extending portion of said bushing.

2. An operator assembly for a jalousie operating mechanism; comprising a separate bearing member attachable to a side rail of a jalousie frame and having a bore therethrough, a handle having a hub upon one side of said bearing member, a pin anchored within said hub and having a polygonal portion extending axially of said bore, said pin being provided beyond the other side of said bearing member with a projecting threaded end portion, a bushing at one end of and separate from said hub, said bushing having a portion extending axially of said bore and nonrotatably sleeved upon the polygonal portion of said pin, the axially extending portion of said bushing being rotatable within said bore and constituting the pivot for said handle, a rock arm nonrotatably mounted on the projecting end portion of said bushing and having a portion attachable to an actuating bar for the jalousie operating mechanism for operating the same from said handle, and means engaging the threaded end portion aforesaid of said pin adjacent said rock arm and cooperating with said hub for retaining the axially extending polygonal portion of said pin in assembled relation with the axially extending portion of said bushing.

3. An operator assembly for a jalousie operating mechanism; comprising a bearing member having a bore therethrough, a handle having a hub upon one side of said bearing member, a pin anchored within said hub and having a polygonal portion extending axially of said bore, said pin being provided beyond the other side of said bearing member with a projecting end portion, a bushing at one end of and separate from said hub, said bushing having a portion extending axially of said bore and nonrotatably sleeved upon the polygonal portion of said pin, the axially extending portion of said bushing being rotatable within said bore and constituting the pivot for said handle, a rock arm nonrotatably mounted on one of the axially extending portions aforesaid and having a portion attachable to an actuating bar for the jalousie operating mechanism for operating the same from said handle, and means engaging the projecting end portion aforesaid of said pin adjacent said rock arm and cooperating with said hub for retaining the axially extending polygonal portion of said pin in assembled relation with the axially extending portion of said bushing.

4. An operator assembly for a jalousie operating mechanism; comprising a separate bearing member attachable to a side rail of a jalousie frame and having a bore therethrough, a handle having a hub upon one side of said bearing member, a pin anchored within said hub and having a polygonal portion extending axially of said bore, said pin being provided beyond the other side of said bearing member with a projecting threaded end portion, a bushing at one end of and separate from said hub, said bushing having a portion extending axially of said bore and nonrotatably sleeved upon the polygonal portion of said pin, the axially extending portion of said bushing being rotatable within said bore and constituting the pivot for said handle, a rock arm nonrotatably mounted on one of the axially extending portions aforesaid and having a portion attachable to an actuating bar for the jalousie operating mechanism for operating the same from said handle, and means engaging the threaded end portion aforesaid of said pin adjacent said rock arm and cooperating with said hub for retaining the axially extending polygonal portion of said pin in assembled relation with the axially extending portion of said bushing.

5. An operator assembly for a jalousie operating mechanism; comprising a separate bearing member attachable to a side rail of a jalousie frame and having a bore therethrough, a handle having a hub upon one side of said

bearing member, a pin anchored within said hub and having a polygonal portion extending axially of said bore, said pin being provided beyond the other side of said bearing member with a projecting end portion, a bushing at one end of and separate from said hub, said bushing having a portion extending axially of said bore and nonrotatably sleeved upon the polygonal portion of said pin, the axially extending portion of said bushing being rotatable within said bore and constituting the pivot for said handle, a rock arm nonrotatably mounted on one of the axially extending portions aforesaid whereby said rock arm may be moved by said handle, said rock arm having a pivotal connection with a substantially aligned actuating bar for the jalousie operating mechanism, said rock arm being adapted to abut and be stopped by a portion of said side rail during movement of said rock arm in one direction, the pivotal connection aforesaid being movable beyond its dead center when said rock arm is moved into abutting stopped relation with the portion aforesaid of said rail to lock said actuating bar in a predetermined position, and means engaging the projecting end portion aforesaid of said pin adjacent said rock arm and cooperating with said hub for retaining the axially extending polygonal portion of said pin in assembled relation with the axially extending portion of said bushing.

6. An operator assembly for a jalousie operating mechanism; comprising a bearing member attachable to a jalousie frame and having a transversely extending substantially horizontal bore therethrough, a handle having a hub upon one side of said bearing member, a pin having a portion anchored within said hub and having a polygonal portion extending axially of said bore, a bushing beside and separate from said hub, said bushing having a portion nonrotatably sleeved upon the polygonal portion of said pin and extending axially of said bore, the axially extending portion of said bushing being rotatable within said bore and constituting a pivot for said handle, a rock arm nonrotatably mounted upon one of the axially extending portions aforesaid and attachable to actuating means for the jalousie operating mechanism for operating the same from said handle, said pin being provided beyond said rock arm with a free end portion, and means cooperating with said hub for retaining the axially extending portions aforesaid in assembled relation with each other and with said bearing member, including an element engaging the free end portion of said pin adjacent said rock arm.

7. An operator assembly for a jalousie operating mechanism; comprising an elongated bearing member attachable to a jalousie frame, said bearing member having an intermediate portion adapted to fit within either of two openings respectively in said jalousie frame to transmit operating stresses directly to said frame and having end portions adapted to overlap the adjacent edges of the selected opening and attachable to said jalousie frame, said bearing member having a transversely extending substantially horizontal bore therethrough, an operating handle upon one side of said bearing member, a rock arm upon the other side of said bearing member and attachable to actuating means for the jalousie operating mechanism, a torque transmitting connection between said handle and rock arm including an extension of said handle having a polygonal portion extending axially of the bore in said bearing member, and a bushing separate from said handle nonrotatably sleeved on the polygonal portion of said extension and rotatable within the bore in said bearing member.

8. An operator assembly for a jalousie operating mechanism; comprising a bearing member attachable to a jalousie frame and having a transversely extending substantially horizontal bore therethrough, an operating handle upon one side of said bearing member, a rock arm upon the other side of said bearing member and having a pivotal connection with a substantially aligned actuating

bar for the jalousie operating mechanism, a torque transmitting connection between said handle and rock arm extending axially of the bore in said bearing member and operable to move said rock arm in opposite directions about the axis of said torque transmitting connection, said rock arm being adapted to abut and be stopped by a portion of said jalousie frame during movement of said rock arm in one direction, the pivotal connection aforesaid being movable beyond its dead center when said rock arm is moved into abutting stopped relation with the portion aforesaid of said jalousie frame to lock said actuating bar in a predetermined position.

9. An operator assembly for a jalousie operating mechanism; comprising a bearing member attachable to a jalousie frame and having a transversely extending substantially horizontal cylindrical bore therethrough, an operating lever handle upon one side of said bearing member, a rock arm upon the other side of said bearing member and attachable to actuating means for the jalousie operating mechanism, a torque transmitting connection between said lever handle and said rock arm including an extension of said lever handle having a polygonal portion extending axially of the bore in said bearing member, and a bushing separate from said handle, interiorly conforming to and fitting about the polygonal portion of 25 said extension, and exteriorly conforming to and rotatable

5 within the cylindrical bore in said bearing member, said lever handle and said rock arm being relatively positioned with an included angle therebetween that is approximately one-half the angular magnitude between adjacent sides of the polygonal portion of said extension, said polygonal portion of said extension being adapted to be removed from and replaced in said bushing whereby the lever handle may be changed from an angular position relative to one side of said rock arm to an equal angular position relative to the opposite side thereof by shifting the engagement of the polygonal portion of said extension from one side to the next thereof with said bushing.
